UNITED STATES PATENT OFFICE.

ELLA F. DE FOREST, OF NEW CANAAN, CONNECTICUT.

DESIGN FOR A TOBACCO-BOX.

53,706.

Specification for Design.

Patented Aug. 19, 1919.

Application filed February 26, 1919. Serial No. 279,448. Term of patent 14 years.

To all whom it may concern:

Be it known that I, ELLA F. DE FOREST, a citizen of the United States, and a resident of New Canaan, in the county of Fairfield and State of Connecticut, have invented a new, original, and ornamental Design for a Tobacco-Box, of which the following is a specification, reference being had to the accompanying drawing, forming a part thereof, wherein—

Figure 1 represents a front view of my design, and

Fig. 2 a side view of the same.

The design comprises a flat body portion with curved edges and a curved bottom. The cover is flat and fits the contour of the upper or flat end of the box.

What I claim and desire to secure by Letters Patent is:

The ornamental design for a tobacco box substantially as shown and described.

ELLA F. DE FOREST.
